US0D1051067S

(12) **United States Design Patent** (10) **Patent No.:** **US D1,051,067 S**
(45) **Date of Patent:** **** Nov. 12, 2024**

(54) **MULTI-HEAD CABLE CONNECTOR WITH FLEXIBLE FINGERS**

(71) Applicant: **Crestron Electronics, Inc.**, Rockleigh, NJ (US)

(72) Inventors: **Howard Balch**, Bloomingdale, NJ (US); **Sae Jhun**, Bayside, NY (US); **Don Florezak**, Tenafly, NJ (US)

(73) Assignee: **Crestron Electronics, Inc.**, Rockleigh, NJ (US)

(**) Term: **15 Years**

(21) Appl. No.: **29/826,059**

(22) Filed: **Feb. 9, 2022**

(51) LOC (14) Cl. **13-03**

(52) U.S. Cl.

USPC **D13/147; D14/433**

(57) **CLAIM**

The ornamental design for a multi-head cable connector with flexible fingers, as shown and described.

DESCRIPTION

FIG. 1 is a top perspective view of a multi-head cable connector with flexible fingers according to our new design; FIG. 2 is a front perspective view thereof;

FIG. 3 is a front elevation view thereof;

FIG. 4 is a rear elevation view thereof; and,

FIG. 5 is a side elevation view thereof.

The broken lines in the drawings are for the purpose of illustrating portions of the article that form no part of the claimed design.
